CLAIM

The ornamental design for decorative panel, as shown and described.

DESCRIPTION

FIG. 1 is a top left front perspective view of the decorative panel of the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a top right perspective view thereof.

The portions of the decorative panel illustrated in broken lines form no part of the design.
